UNITED STATES PATENT OFFICE.

WILLIAM WALTER HUDSON, OF SALT LAKE CITY, UTAH.

LOADER CONVEYER.

Application filed February 18, 1925. Serial No. 10,100.

To all whom it may concern:

Be it known that I, WILLIAM W. HUDSON, a citizen of the United States, and a resident of Salt Lake City, in the county of Salt Lake 5 and State of Utah, have invented certain new and useful Improvements in Loader Conveyers, of which the following is a specification.

My invention is an improvement in loader 10 conveyers, and it consists in the combinations, constructions and arrangements herein described and claimed.

An object of the invention is to provide a conveyer which can be adjusted quickly 15 and easily to conduct material to a given point from any point within a considerable area.

A further object of the invention is the provision of a conveyer of the character 20 described which is light in weight, can be moved readily from place to place, and which therefore is particularly well adapted for use in a mine or like underground place.

Other objects and advantages of the invention will be apparent from the following description, considered in conjunction with the accompanying drawings, in which:

Figure 1 is a plan view of the improved conveyer,

Figure 2 is a side elevation of the conveyer,

Figure 3 is a fragmentary vertical section through the conveyer, the view being taken substantially along the line 3—3 of

Figure 4, and

Figure 4 is a fragmentary vertical section taken substantially along the line 4—4 of Figure 3.

The conveyer embodying the invention 40 comprises a lower conveyer unit or section indicated generally at 1, a truck 2 on which the conveyer unit 1 is supported for movement along a track 3 or on any supporting surface, an upper conveyer unit or section 45 4, and a carriage 5 to which the upper conveyer unit 4 is swivelly attached, the carriage 5 being adapted to move long the lower conveyer unit 1.

The truck 2 comprises a pair of wheels 50 6 mounted on an axle 7 and preferably being flanged and spaced for rolling contact with the rails of the track 3. The track 3 may be of any standard gage. The frame of the truck 2 comprises a base portion 8 55 rockingly supported on the axle 7. Stand-

ards are upstanding from the corner portions of the base and each standard comprises an upper section 9 and a lower section 10 adjustably connected as at 11 so that the effective height of the standards can be 60 varied within a considerable range. The truck 2 also includes a pair of upper side supporting members 12, each of which is secured at its opposite ends to the upper end portions of the standards at that side of 65 the truck by rivets 13 or like fastening devices. Side clamping plates 14 are secured to the side supporting members 12, as by means of rivets 15, and extend above the level of the side supporting members 12 for 70 engagment with lateral faces of the side members 16 of the frame structure lower conveyer unit 1. The clamping plates 14 at the opposite ends of the truck are spanned by tie rods 17 which extend through 75 alined openings in such clamping plates, and have threaded end portions engaged by nuts 18 whereby when the nuts 18 are tightened the upper end portions of the clamping plates at opposite sides of the truck 80 will grip the lower conveyer and hold the lower conveyer against longitudinal and lateral movement on the truck. When the nuts 18 have been loosened, the lower conveyer 1 can be moved longitudinally on the truck 85 within the elements set by the length of the lower conveyer, and secured to the truck in adjusted position on the latter by means of the nuts 18 and the tie rods 17.

The respective side members 16 of the lower conveyer unit have alined bearings 19 at one end of the lower conveyer for a shaft 20, and have alined bearings 21 at the other end of the lower conveyer for a shaft 22. The shaft 20 is located at the head or delivery end of the lower conveyer unit, and is driven by a prime mover, not shown, with which it is suitably connected in any suitable known manner.

The prime mover may be any suitable 100 motor, such as a compressed fluid motor adapted for connection with any suitable source of compressed fluid. The shaft 20 carries a roller 23, which is secured thereto. The shaft 22 carries a roller 24 which is an idler. A conveying belt 25 is trained about the rollers 23 and 24 and extends between the side members 16 of the lower conveyer and over carrying rollers 26 which are rotatably supported on cross rods 27 105

which extend between the upper edge portions of the side members 16 at intervals along the length of the lower conveyer.

The lower conveyer has side boards for retaining material against lateral displacement from the conveyer belt 25, each of the side boards comprising an angle iron 28 substantially co-extensive in length with the side members 16 and having depending securing lugs 29 received in sockets 30 in the upper side of one of the side members 16 adjacent to the inner edge of the latter. The angle iron 28 has extensions in the form of strips 31 and 32 respectively attached to the flanges of the angle iron. The strips 31 and 32 may be of leather or any other suitable flexible and durable material.

The upper conveyer unit 4 is similar to the lower conveyer 1 in construction and comprises a pair of side members 16' connected by cross rods 26' on which are rotatably supported carrying rollers 27'. The side members 16' of the upper conveyer have alined bearings 19' at the delivery end of the upper conveyer for a shaft 20' which is operatively connected in any suitable known manner to the drive mechanism of a prime mover 23' which preferably is a compressed fluid motor. The side members 16' of the upper conveyer have alined bearings 21' at the receiving end of the upper conveyer for a shaft 22' which carries an idler roller 24'. A conveyer belt 25' is trained about a driven roller 23' on the shaft 20' and about the idler roller 24' and passes across the carrying rollers 27'. The bearings 19' preferably are integral portions of plates 33 which are secured, as at 34 to the end portions of the side members 16' at the discharge end of the upper conveyer unit. These plates 33 have end extensions at 35, each formed with a vertical opening 36 adapted to be placed in vertical alinement with an opening 37 in the corresponding lateral edge portion of the floor or base plate 38 of the carriage 5. A pivot pin 39 can be placed in the alined openings 36-37 at either of the opposite sides of the carriage 5 for attaching the upper conveyer swivelly to the floor of the carriage 5.

The upper conveyer also has side board arrangements corresponding to the side board arrangements of the lower conveyer. The parts of the side board arrangements of the upper conveyer have been designated by the same reference numerals primed as the like parts of the side board arrangements of the lower conveyer and it therefore is thought that no detailed description of the side board arrangements of the upper conveyer need be given herein.

The receiving end of the upper conveyer carries a scoop 40 in the form of a plate secured, as at 41, to the side members 16' of the upper conveyer,

The base 38 of the carriage 5 is mounted on a pair of wheels 42 spaced apart for rolling contact with the upper faces of the side members 16 outwardly of the lugs 28. The base 38 of the carriage has depending guiding and retaining lugs 43 at opposite sides thereof depending below the level of the side members 16 for engaging with the outer faces of the side members 16 to prevent lateral displacement of the carriage 5 from the side members 16 of the lower conveyer.

From the foregoing description of the various parts of the device, the operation thereof may be readily understood. The truck 2 can be moved along the track 3 to a desired position and the effective height of the truck can be adjusted as desired within limits by adjusting the length of the standards 9-10. The upper conveyer unit 4 and the carriage 5 can be moved as a unit along the lower conveyer to adjust the effective length of the conveyer as a whole. If desired, the upper conveyer can be swung about the axis of the vertical pin 39 so that material can be loaded from a point at one side of the track. When the upper conveyer unit is to be swung laterally of the left hand side of the lower conveyer unit, the pivot pin 39 is placed in the opening 36 at the left hand side of the upper conveyer unit and the opening 37 at the left side of the carriage 5. When it is desired to swing the upper conveyer unit to the right of the lower conveyer unit, the pivot pin 39 is placed in the opening 36 at the right hand side of the lower conveyer unit and the opening 37 at the right hand side of the carriage. The floor plate of the carriage 5 is cut away as indicated at 44 in Figure 1 so that material discharged from the upper conveyer unit will fall onto conveying belt 25 of the lower conveyer unit and will be discharged from the lower conveyer unit at the head of the latter into any desirable place. The scoop 40 may serve as a guide along which shovels may be slid to deliver material onto the conveyer belt 25' at the receiving end of the upper conveyer unit.

It will be obvious from the foregoing that the invention provides a conveyer which can be used effectively in a very limited space and also in a space of considerable area to conduct material from any point within that area to a given point. The device is light in weight and at the same time is strong and durable.

Obviously, the invention is susceptible of embodiment in forms other than that which has been illustrated in the accompanying drawings and I therefore consider as my own all such modifications and adaptations thereof as fairly fall within the scope of the appended claims.

I claim:

1. A conveyer comprising a lower conveyer

- unit, a truck supporting the lower conveyer unit, a carriage movable along the lower conveyer unit, and an upper conveyer unit swivelly attached at one end to said carriage.
- 5 2. A conveyer of the character described comprising a truck having a base rockingly supported on wheels, standards upstanding from the corner portions of said base, said standards being adjustable to vary the
- 10 height thereof, supporting side beams secured to the upper ends of said standards, a lower conveyer unit comprising a pair of spaced side members adapted to rest on said supporting side members of the truck,
- 15 clamping plates disposed at opposite sides of the truck and extending above said supporting side members for contact with the outer faces of said side members of the conveyer unit, and adjustable means connecting
- 20 clamping plates at opposite sides of the truck for maintaining said clamping plates releasably in clamping engagement with said lower conveyer unit, and an upper conveyer unit movably supported on said lower
- 25 conveyer unit.
3. A conveyer comprising a movably supported lower conveyer unit and an upper conveyer unit, each of said conveyer units comprising a pair of spaced side members, a plurality of spaced carrying rollers mounted between the upper edge portions of said side members, a driven roller mounted between said side members at the delivery end of the conveyer unit, an idler roller mounted
- 30 between the side members at the opposite end of the conveyer unit, a conveyer belt trained about said driven roller and said idler roller and passing over said carrying rollers, and a carriage movable along the
- 35 upper side of said lower conveyer unit and supporting the delivery end of said upper conveyer unit.
4. In a conveyer of the character described, a lower conveyer unit comprising a pair of spaced side members and conveying means disposed between said side members, a carriage comprising a base plate, a pair of wheels movably supporting said base plate, said wheels being spaced apart for
- 40 rolling contact with the upper faces of said side members of the lower conveyer unit, pendent guiding and retaining lugs at opposite sides of said base plate engaged with
- 45 the outer faces of said side members of the lower conveyer unit to hold said carriage against lateral displacement from said lower conveyer unit, an upper conveyer unit having a pair of spaced side members and conveying means between the side members,
- 50 and means for attaching an end portion to said upper conveyer unit to said carriage.
5. In a conveyer of the character described, a lower conveyer unit comprising a pair of spaced side members and conveying means disposed between said side members, a carriage comprising a base plate, a pair of wheels movably supporting said base plate, said wheels being spaced apart for
- 55 rolling contact with the upper faces of said side members of the lower conveyer unit, pendent guiding and retaining lugs at opposite sides of said base plate engaged with the outer faces of said side members of the lower conveyer unit to hold said carriage against lateral displacement from said lower
- 60 conveyer unit, an upper conveyer unit having a pair of spaced side members and conveying means between the side members,
- 65 and means for attaching an end portion to said upper conveyer unit to said carriage.
- 70
6. In a conveyer of the character described, a lower conveyer unit comprising a pair of spaced side members and conveying means disposed between said side members, a carriage comprising a base plate, a pair of wheels movably supporting said base plate, said wheels being spaced apart for
- 75 rolling contact with the upper faces of said side members of the lower conveyer unit, pendent guiding and retaining lugs at opposite sides of said base plate engaged with the outer faces of said side members of the lower
- 80 conveyer unit to hold said carriage against lateral displacement from said lower
- 85 conveyer unit, an upper conveyer unit having a pair of spaced side members and conveying means between the side members,
- 90 and means for attaching an end portion to said upper conveyer unit to said carriage.
